LAMP SHADE

Arthur Jones, 1810 Demaree Lane,
Houston, Tex. 77029

Filed Dec. 6, 1965, Ser. No. 101

Term of patent 14 years

(Cl. D48—16)

FIG. 1 is a perspective view of a lamp shade, showing my new design;

FIG. 2 is a fragmentary elevational view of the shade pattern on an enlarged scale; and showing the arrangement of the apertures and indentations; and

FIG. 3 is a fragmentary view of one of the indentations which form part of the pattern as shown in FIGS. 1 and 2.

The broken line showing of a lamp base in FIG. 1 is for illustrative purposes only.

I claim:

The ornamental design for a lamp shade, as shown and described.
